APPARATUS FOR DRYING AND
CONDITIONINGBliss M. Jones, Orange, Mass., assignor to Rod-
ney Hunt Machine Company, Orange, Mass.,
a corporation of Massachusetts

Application September 5, 1939, Serial No. 293,372

4 Claims. (Cl. 34—32)

The subject matter of this invention relates primarily to apparatus for the quick drying and conditioning of materials, as for instance, cloth, yarn, raw stock, thread, etc., and samples thereof. However, the same apparatus may be used with regard to such widely varying materials as pills and pharmaceutical supplies, tobacco and other vegetable products, and samples of these and other objects.

When dyeing large batches of cloth, yarn, etc., textile mills must take samples from the batch at intervals, in order to determine whether the dyeing operation has proceeded long enough to obtain the color or shade desired. The samples must be completely dried and brought into balance with the atmosphere or room humidity, so that the true color of the sample can be seen. The longer the period of time spent in drying and conditioning the sample, the more error in final color is made, since the batch of material being dyed has naturally been in the dye that much longer than the dry sample, and therefore the batch has absorbed more dye than the dry sample.

Hence it is clear that speed in drying and conditioning the sample is greatly desired, since the quicker the sample can be used for comparison, the less error in matching colors is made.

Heretofore it has been the practice to locate the sample stationarily and to blow or circulate heated air about it until it is dry, then wave the sample in the air, by hand, for about fifteen minutes until the heat has left it. At this point the sample is in dried and conditioned state for matching, but at least twenty or thirty minutes has elapsed, and meanwhile the batch being dyed has absorbed that much more dye.

The objects of this invention include the provision of apparatus to obviate the difficulties above mentioned; the provision of apparatus whereby the time of drying and conditioning materials may be reduced from twenty to thirty minutes to a few seconds; the provision of apparatus wherein articles may be moved through heated air at very high speed and in a direction perpendicular to the main line of force of the air, the air being thereby forced through the articles (such as cloth, yarn, etc.); and the provision of such apparatus wherein after the quick drying, the articles are forced through unheated air at high speed to be brought into balance with room atmosphere.

Other objects and advantages of the invention will appear hereinafter.

Reference is to be had to the accompanying drawing, in which—

Fig. 1 is a front elevation of the device with parts in section;

5 Fig. 2 is a view in section on line 2—2 of Fig. 1; and

Fig. 3 is a perspective view showing means for holding a cloth sample on a screen element.

In the drawing, the numeral 10 indicates a 10 portable box-like enclosure having sides 12, top and bottom elements 14, and front and rear walls 16 and 18, respectively. The front wall extends only part way to the top element 14, and at the top of the front wall there is hinged a door 20 15 whereby to completely close the box.

Journalled in the center of the rear wall 18 is a 20 shaft 22 driven by a motor 24 which motor may be supported by any convenient means, as by a bearing. Shaft 22 extends into the box and

25 carries therewith a sleeve 26 of any suitable material, such as wood or metal. A number of L-shaped rods 28 of material similar to that of the sleeve are anchored at one end in the outer end of sleeve 26, as shown in Fig. 2, and have their 30 other ends secured to a large but light weight disc 30, said disc being keyed or otherwise secured to shaft 22 at the inner end of sleeve 26. Extending forwardly from the disc are a plurality of rods 32, equal in number to the L-shaped rods 35 28, but each rod 32 is positioned somewhat in advance of its corresponding rod 28, in the direction of rotation of the disc, as shown in Fig. 1.

The above described structure provides a 40 rotary device with supports made up of rods 28, 32, for the reception of wire screens 34, attached between each corresponding pair of the rods. These screens are seen to be tilted forward in the direction of rotation of the device, due to the 45 relative positions of the rods, and are secured thereto by any convenient or desired means.

Conveniently located in the box or enclosure 10 are electric or other heating units 36 for heating the air in the box. These units are shown only generally as their construction and operation 45 are well known.

In the operation of the device, the samples of cloth, or other material, are fastened to the forward faces of the wire screens 34 by means of pins, clips, or other convenient or desired means. 50 The door 20 is closed, and the heater elements and motor 24 are turned on. Supposing the radius of the disc 30 to be about 6 inches, and the motor speed to be 1700 R. P. M., the approximate speed of the samples will be 5100 feet per minute. This high speed will force the heated

air directly through the cloth or other material and in a few seconds the material will be dry. Then the door 20 is opened, the heater elements are turned off, and in a few more seconds all the heat has been forced out of the material and it has come to balance with room heat and humidity, and is ready for comparison. The inclination of the screens prevents the air from slipping past the ends thereof as would be the case if the screens were radial, and therefore the largest possible amount of air is forced through the material. In effect, the screens 34 meet the air perpendicularly to the force thereof, instead of at an angle.

Drying depends on two factors primarily—heat 15 and amount of air movement. In the conventional dryer using fans, the movement of air is relatively low, and to approximate the result obtained by this invention, i. e., the equivalent of 5100 feet of air per minute, in the case of a disc of 6 inch radius, such a large fan would be necessary as to be prohibitive in cost. Also, only one or two samples can be dried at one time by a fan, but this invention allows four (as shown) or more to be processed at once.

Having thus described my invention and the advantages thereof, I do not wish to be limited to the details herein disclosed, otherwise than as set forth in the claims, but what I claim is:

1. In a material conditioning apparatus of the class described, a rotary support, means to rotate said support at a high speed, an element substantially parallel to the axis of the support and secured thereto adjacent its periphery, a second element substantially parallel to said axis and secured to the support between said first element and said axis, but to one side of a line connecting said first element and said axis, and

a pervious material holding means secured to and between said elements.

2. In a drying and conditioning apparatus of the class described, a rotary carrier comprising a 5 journaled support, means to rotate said support at high speed, two rod-like elements extending from said support substantially parallel to the axis of said carrier and at different distances from said axis, said elements being out of radial alignment, the element farther from said axis being located forwardly of the other element in the direction of rotation of said carrier, and a pervious material support mounted on and between said elements.

3. In an apparatus of the class described, a box-like enclosure having a door in one wall, a shaft adapted to be driven at a high speed journaled in the opposite wall and extending into the enclosure, a collar fixed to the shaft for rotation therewith, a disc fixed to the shaft, a plurality of rods extending from said disc so as to overlie the collar, certain of said rods being located closer to the collar than the other rods and having angled ends extending to and secured to the collar, and a wire screen fixed between pairs of said rods.

4. In a drying and conditioning apparatus, a rotary support, means to rotate said support at high speed, pervious sample holding means on 30 the support, and arranged parallel to the rotative axis thereof but non-radially with respect thereto, said holding means having a leading edge located in advance of a trailing edge in the direction of rotation of said support, said leading edge being at a greater distance from said axis than said trailing edge, and means adapted to secure a sample to said holding means.

BLISS M. JONES.
